[57] CLAIM

The ornamental design for a water distribution tray for an in-duct humidifier, as shown and described.

DESCRIPTION

FIG. 1 is a top perspective view of a water distribution tray for an in-duct humidifier showing our new design.

FIG. 2 is a bottom perspective view thereof.

FIG. 3 is a top plan view thereof.

FIG. 4 is a bottom plan view thereof.

FIG. 5 is a side elevation view thereof, the opposite side being a mirror image of that shown; and,

FIG. 6 is an end elevation view thereof, the opposite end being a mirror image of that shown.
